UNITED STATES PATENT OFFICE

168,168

SEWING MACHINE

Phillip S. Morse, New York, N. Y.

Application August 21, 1952, Serial No. 21,147

Term of patent 14 years

(Cl. D70—1)

To all whom it may concern:

Be it known that I, Phillip S. Morse, a citizen of the United States of America and a resident of the city of New York, in the county of Bronx and State of New York, have invented a new, original, and ornamental Design for a Sewing Machine, of which the following is a specification, reference being had to the accompanying drawing, forming a part thereof.

Fig. 1 is a front elevational view of a sewing machine showing my new design;

Fig. 2 is a rear view thereof;

Fig. 3 is a top view thereof;

Fig. 4 is a side elevational view thereof; and

Fig. 5 is a side elevational view of the opposite end to that of Fig. 4.

My design is characterized by those features shown in full lines.

I claim:

The ornamental design for a sewing machine, substantially as shown.

PHILLIP S. MORSE.
